UNITED STATES PATENT OFFICE.

CHARLES F. FLEMMING, OF AKRON, OHIO, ASSIGNOR TO THE MILLER RUBBER COMPANY, OF AKRON, OHIO, A CORPORATION OF OHIO.

DESIGN FOR A SPONGE DOLL.

59,550.

Specification for Design.

Patented Nov. 1, 1921.

Application filed June 29, 1921. Serial No. 481,407. Term of patent 7 years.

To all whom it may concern:

Be it known that I, CHARLES F. FLEMMING, a citizen of the United States, residing at Akron, in the county of Summit and State of Ohio, have invented a new, original, and ornamental Design for Sponge Dolls, of which the following is a specification, reference being had to the accompanying drawing, forming part thereof.

The figure is a perspective view of a sponge doll, showing my new design.

I claim:

The ornamental design for a sponge doll, as shown.

CHARLES F. FLEMMING.
